(No Model.)

A. J. KLETZKER.
Fountain Pen.

No. 240,909.

Patented May 3, 1881.

FIG. 1.

FIG. 2.

FIG. 3.

ATTEST:

Robert Burns

George Bullock

INVENTOR:

Albert J. Kletzker

UNITED STATES PATENT OFFICE.

ALBERT J. KLETZKER, OF ST. LOUIS, MISSOURI.

FOUNTAIN-PEN.

SPECIFICATION forming part of Letters Patent No. 240,909, dated May 3, 1881.

Application filed November 23, 1880. (No model.)

To all whom it may concern:

Be it known that I, ALBERT J. KLETZKER, a citizen of the United States, residing at St. Louis, in the State of Missouri, have invented 5 certain new and useful Improvements in Autographic Fountain-Pens; and I do hereby declare that the following is a full, clear, and exact description of the invention, which will enable others skilled in the art to which it applies to make and use the same, reference being had to the accompanying drawings, forming part of this specification.

This invention consists—

First, in the provision, in a fountain-pen, of 15 a flexible slitted barrel-pen or writing-point, connected to and operating a needle clearer or valve, by which the flow of ink to the pen is regulated and controlled.

Secondly, in the provision, on a slotted writing-point for fountain-pens, of a projecting toe 20 for operating the clearer needle or valve, as will hereinafter more fully appear.

Thirdly, in the provision, in a fountain-pen, 25 of a clearer needle or stem provided with duplicate valves which rest in corresponding seats in the casing of the pen to shut off the flow of the ink when the pen is not in use. It is preferred to make these valves self-closing, and this is accomplished by means of a spiral 30 spring which is preferably arranged within the air-tube out of contact with the ink, so as not to be corroded or affected in any manner by the same, all as will hereinafter more fully appear.

Fourthly, in the provision, in a fountain-pen, 35 of a needle clearer or valve having a valve which controls both the ink and air openings, so as to place the flow of ink entirely under control and prevent any leakage when the pen is not in use.

Fifthly, in certain details of construction, as 40 will hereinafter more full appear.

In the drawings, Figure 1 is an enlarged vertical section. Fig. 2 is a detail section of the writing portion. Fig. 3 is a perspective view 45 of the writing-barrel point.

The hollow fountain or ink-handle A is of any usual shape and construction, having its top formed with a valve-seat for the valve b of the screw-cap B.

C is a slitted writing-point, which is of a cylindrical shape at its upper end, where it is at-

tached to the point-holder D by screwing there-in or fastened in any other suitable manner. The point C is provided with a projecting toe, c, to which the lower end of the clearer needle or stem e' is attached so as to be drawn down by the springing of the point C in use. This springing of the writing-point and the consequent movement of the clearer in the bore of said point is continuous during the use of the pen, so that said bore or passage will be kept clear and a constant supply of ink carried to the writing-point. The toe c is preferably formed on the writing-point in the manner shown in Fig. 3, so that the spring of the writing-point will be above said toe, so as to impart the necessary movement to the same.

The point-holder D is removably attached to the tapering-point section E, so as to be easily detached for cleaning purposes, &c.

In use any suitable material, either vulcanite, celluloid, metal, &c., may be used in the construction of the handle A, cap B, tapering-point section E, and point-holder D, and the slitted writing-point C will be of any suitable 75 metal, such as gold, steel, &c.

The clearer or stem e' is formed with plug-valves c² c³, which are seated in suitable valve-seats on the cylindrical portion of the point C and the bottom of the handle A, as shown, and 80 the valve c³, in addition to controlling the ink-supply, also controls the air-supply openings a of the air or vent tube A', so as to render the flow of ink more regular and automatic. The needle clearer or stem e', with its valves c² c³, 85 are drawn upward by a spring, a', arranged within the air-tube A', as shown. The stem-extension e⁴, on which the spring acts, passes up through the air-supply opening a, as clearly shown in Fig. 1.

The air-tube A' is attached to the side of the ink-receptacle A, so as to form a stronger and more rigid connection, and it is provided with a vent-hole, a², near its upper end, as shown.

The toe c may be formed on or attached to the writing-point in any suitable manner without departing from the spirit of my invention.

I am aware that prior to my invention fountain-pens have been constructed with slitted writing-points in connection with clearerneedles; but in such cases the needle-clearers rested directly on the paper, and were not at-

tached to or operated by the writing-point, as in my construction.

I am also aware that it is not new to operate an ink-controlling valve in a fountain-pen by the springing of the pen-point in use, such construction being shown in Patent No. 70,453, issued November 5, 1867, to G. R. Metten, for an improvement in fountain-pens. I therefore do not claim such combination broadly; but

10. What I do claim as my invention is—

1. In a fountain-pen, a barrel or slitted writing-point connected to and operating a needle-clearer by the springing of the pen-point in use, said clearer having valve or valves for controlling the flow of ink, substantially as and for the purpose set forth.

2. The combination, with a fountain-pen having a vertically-moving needle or clearer, c' , of a slitted pen or writing-point, C, provided with 20 a toe or projection, c , for operating said needle-clearer, substantially as and for the purpose set forth.

3. The combination, in a fountain-pen, of a barrel or slitted pen-point, C, connected to and 25 operating a needle-clearer, c' , having valves c^2 c^3 , situated as described and opening downward, in the manner herein described, and for the purpose set forth.

4. The combination, in a fountain-pen having a barrel or slitted writing-point, C, of the 30 needle-clearer c' , drawn upward by a spring, a' , and having valves c^2 c^3 , situated as described and opening downward, in the manner herein described, and for the purpose set forth.

5. The combination, in a fountain-pen having a barrel or slitted writing-point, C, and a needle-clearer, c' , provided with valves c^2 c^3 , situated as described and opening downward, of the spring a' , arranged in the air-tube A', all as herein described, and for the purpose set 40 forth.

6. The combination of the ink-chamber and air-tube, having their outlet-openings situated as described, with the needle-clearer, having a valve, c^3 , controlling the ink and air supply 45 openings, as described, and for the purpose set forth.

In testimony whereof witness my hand this 18th day of November, 1880.

ALBERT J. KLETZKER.

In presence of—

W.M. MENART,
ROBERT BURNS.
